UNITED STATES PATENT OFFICE.

JOHN A. BRILL, OF PHILADELPHIA, PENNSYLVANIA.

DRAW-HEAD FOR RAILWAY-CARS.

SPECIFICATION forming part of Letters Patent No. 357,812, dated February 15, 1887.

Application filed November 11, 1886. Serial No. 218,516. (No model.)

To all whom it may concern:

Be it known that I, JOHN A. BRILL, a citizen of the United States, residing at Philadelphia, in the county of Philadelphia and State 5 of Pennsylvania, have invented certain new and useful Improvements in Draw-Heads for Railway-Cars, of which the following is a specification.

My invention has relation to couplers or draw-heads for railway-cars.

In some systems of railways, particularly that in which gravity is used for running or propelling the cars at points or distances on the line of way and horse-power is employed, 15 for propelling the cars over the other or remaining points or distances on the line to provide a combined gradient and horse-power railway, it is essential to have a draw-head for the cars which admits of coupling one car 20 to another, which draw-head also serves as a bumper, and which admits of having attached to it a pole, single-tree, or analogous device for applying horses to and detaching them from the cars at the intervals whereat they 25 are used for propelling the car.

My invention, therefore, has for its object to provide a combined draw-head and bumper adapted to be coupled to a like meeting draw-head, and also to receive and have coupled to 30 it a pole, single-tree, or like attachment.

My invention, accordingly, consists of the combination, construction, and arrangement of parts comprising a combined bumper, draw-head, and coupler having means for receiving 35 and firmly retaining in position thereon a pole or single-tree attachment for horses, having reference particularly to a draw-head having a front bumping-face, near the top of which is a slot or mouth having open sides through 40 which passes a coupling-pin for securing the single-tree or pole to the draw-head, a hook or lug upon the top of the draw-head back of said pin for engagement with the link of the coupled draw-head, said link being pivoted 45 to the draw-head slightly to the rear of said hook or lug and is wide enough to pass up and down outside of the draw-heads when placed in engagement with and disengaged from the hook or lug of a meeting draw-head; to a con- 50 cussion-spring, truss, or brace-rod, and supporting-bracket for the draw-head; and to a

safety device for preventing accidental dis- placement of the coupling-pin for the pole or single-tree attachment, which safety device must be manually operated before said pin 55 can be withdrawn from its draw-head socket.

While I have described my improved draw-head as especially applicable to a defined system of railways, yet I do not limit myself thereto, as it may be used upon cars for street 60 or other railways with equal advantage, and I have therefore in the drawings shown a form of draw-head especially adapted for street-railway cars.

In the drawings, Figure 1 represents an ele- 65 vation of a draw-head embodying my improve- ments; Fig. 2, a like view of two draw-heads coupled together, one of them partly broken away; Fig. 3, a plan of the same, partly sec- 70 tional; Fig. 4, an elevation of a slight modifi- cation of draw-head support to adapt it for use upon street-railway cars; and Fig. 5, a de- tail plan of same, partly broken away.

A represents the draw-head, having pref- 75 erably a wide curved front face, *a*, which serves as a bumping end or face, and is preferably in the form of a plate depending from a top plate, *a'*, which plates are united and strengthened by a vertical rib, *a''*, which terminates at its bottom in a screw or threaded end, *a'''*. This 80 plate-and-rib form of draw-head is preferable, as it provides a light, strong, and durable draw-head; but it may be otherwise cast or made, as desired. Above the top plate, *a'*, is a second plate, *B*, or it is a branch or fork 85 from plate *a'*, to form or provide a slot or open space, *b*, above plate *a'*. In branch *B* is an opening, *b'*, through which passes a pin, *C*, which also enters a socket or opening, *a''*, in rib *a''* or draw-head *A*. 90

In the slot or open space *b* is inserted the tongue of the pole or single-tree attachment, which rests upon the top of the draw-head and is retained in position by the pin *C*, which is therefore a coupling-pin only for said pole or 95 single tree attachment and has nothing to do with coupling of two of the similar-described draw-heads together.

Upon the top of plate or fork *B*, back of pin *C*, is a rearwardly-projecting hook or lug, *d*, 100 and below and slightly to the rear of hook *d* a link, *G*, is pivoted or otherwise loosely at-

tached to draw-head A or its stem or rod D. This link G normally assumes a vertical position, as shown in Fig. 1, and is wide enough to pass up and down outside of the draw-heads, as shown in Fig. 3, as the same is raised or lowered to couple with and uncouple from the hook or lug d on a meeting draw-head, as represented in Fig. 2. This outside link, G, therefore, in conjunction with hook 10 or lug d, serves as the coupling device for uniting two of the similar described draw-heads.

To retain the coupling-pin C in position to prevent its accidental displacement by jarring 15 or other causes, to avoid corresponding detachment of the pole or single-tree attachment, it is provided at its upper end with a loose link, c, adapted to engage with lug d. Link c is of such a length that its rear end clears the hook 20 or lug d when the link is raised on its pivot-point by hand or by a chain, e, when the pin C is down or in position in the draw-head.

As the link c is pivoted to pin C, its normal position or engagement with hook d is maintained by gravity, so that if pin C is lifted by 25 jarring, bumping, or other accidental cause, or without first raising the link c, it is drawn toward and engages with hook d to lock the pin and prevent its further elevation out of the 30 draw-head. When coupling two meeting draw-heads, one of the links c is first thrown over to the front of its respective draw-head before the link G on the opposite draw-head is raised into engagement with said hook. 35 (See Fig. 2.) The draw-head stem or rod D passes through suitable openings, h, in the car-sills or cross-timbers H, having face-plates h', and through suitable openings, i, in a right-angle bracket, I, having nipples i' for bolt or 40 screw-fastenings i'' with the car-timbers, said bracket being more plainly shown in Fig. 6.

Between the vertical end i'' of bracket I and timber H is a concussion-spring, L, and also a washer or plate, l, to take the wear off of 45 timber or sill H. The end of stem D, projecting beyond the bracket I, is provided with a suitable cross pin or stud, d'', for contact with the end of spring L, which receives the pulling strains as well as those of concussion, 50 and has a screw or threaded end, d', which is connected to the draw-head end a'' by a truss or brace, M, securely fixed to said ends by nuts m. This brace strengthens the draw-head, its bumping-face, and stem, so that no 55 part of the same will bend or otherwise be easily impaired when in service.

In applying my improved draw-head to street-railway cars the bracket I is continued out to the front end sill or platform of the car, 60 and has an upwardly-projecting plate, N, which passes up in front of and forms a guard-plate for that part of the dasher adjacent to the draw-head. To make this guard-plate light, but strong, its front side is provided at 65 intervals with ribs n, as indicated more plainly

in Fig. 7, and is screwed to the front side and bottom of the sill-piece, as shown in Fig. 4.

This guard-plate and bracket are preferably in one piece. In all other respects the coupler or draw-head is constructed as above described.

What I claim is—

1. A draw-head having a wide and deep solid bumping-face, a slot or open space above and back of the bumping-face, a coupling-pin 75 passing through said slot, a hook or lug back of said pin, and an outside link for coupling one draw-head to another, substantially as set forth.

2. A combined draw-head and bumper having slot or open space b above the bumping-face of the draw-head, a coupling-pin passing through said slot or open space, a hook or lug back of said pin, and an outside coupling-link, G, substantially as set forth. 80

3. A combined draw-head and bumper having a coupling-pin for a pole or single-tree attachment and a coupling device for securing two similar draw-heads together, substantially as set forth. 85

4. The combination, with draw-head A, having slot or open space b, of coupling-pin C, having pivoted link c, hook or lug d, and link G, substantially as set forth. 90

5. The draw-head A, having slot b, threaded ends a'' and d'', and brace-rod M, substantially as set forth. 95

6. The draw-head A, having brace-rod, in combination with bracket I and concussion-spring L, substantially as set forth. 100

7. The draw-head A, having brace-rod M, bracket I, having guard or shield N, and spring L, substantially as set forth. 105

8. In combination with draw-head A, the bracket I, having at its front side a guard or shield, N, provided with ribs n on its front side, substantially as set forth. 110

9. The draw-head A, composed of bumping-plate, a top plate, a', fork B, threaded ends d' and a'', and brace-rod M, substantially as set forth. 115

10. A combined draw-head and bumper, A, having open space or slot b, hook or lug d, coupling-pin C, and safety devices for said pin, substantially as set forth. 120

11. A draw-head having a wide and deep solid bumping-face, a slot or open space above and back of the bumping-face, and a coupling-pin passing through said slot, substantially as set forth. 125

12. A combined draw-head and bumper having a coupling-pin for a pole or single-tree attachment, substantially as set forth.

In testimony whereof I affix my signature in presence of two witnesses.

JNO. A. BRILL.
